UNITED STATES PATENT OFFICE

168,017

DESK TALLY

Clarence W. Braatz, Milwaukee, Wis., assignor to
 Durant Manufacturing Co., Milwaukee, Wis., a
 corporation of Wisconsin

Application January 9, 1952, Serial No. 17,977

Term of patent 14 years

(Cl. D74—1)

To all whom it may concern:

Be it known that I, Clarence W. Braatz, a citizen of the United States residing in the city of Milwaukee, in the county of Milwaukee, and State of Wisconsin, have invented a new, original, and ornamental Design for a Desk Tally, of which the following is a description, reference being had to the accompanying drawing forming a part thereof.

In the drawing:

Fig. 1 is a top plan view of a desk tally embodying my new design;

Fig. 2 is a front elevational view of the desk tally; and

Fig. 3 is an end elevation of the desk tally, the opposite end of the operating bar element being the same in appearance as the end shown here.

The dominant feature of my design is shown in solid lines.

I claim:

The ornamental design for a desk tally, substantially as shown and described.

CLARENCE W. BRAATZ.
